(57) **CLAIM**

The ornamental design for a hanger body, as shown and described.

DESCRIPTION

FIG. 1 is a top, front, and left side perspective view of a first embodiment of a hanger body showing our new design; FIG. 2 is an enlarged top, front, and left side perspective view thereof;

FIG. 3 is an enlarged top, front, and left side perspective view thereof;

FIG. 4 is an enlarged top plan view thereof;

FIG. 5 is an enlarged bottom plan view thereof;

FIG. 6 is an enlarged left side elevational view thereof;

FIG. 7 is an enlarged right side elevational view thereof;

FIG. 8 is an enlarged front elevational view thereof; and,

FIG. 9 is an enlarged rear elevational view thereof.

The broken-line disclosure is for illustrative purposes only and forms no part of the claimed design, and a second embodiment comprises a mirror image of the first embodiment.
